AIR CONDITIONING SYSTEM

Filed March 30, 1938

UNITED STATES PATENT OFFICE

2,244,551

AIR CONDITIONING SYSTEM

Robert B. P. Crawford, Miami, Fla., assignor to
Minneapolis-Honeywell Regulator Company,
Minneapolis, Minn., a corporation of Delaware

Application March 30, 1938, Serial No. 198,850

3 Claims. (Cl. 257—3)

This invention relates to an air conditioning system, and is more particularly concerned with an air conditioning system for cooling and controlling the humidity of a space.

It is customary in such systems to pass outdoor air over cooling coils whereby the temperature as well as the humidity of the air may be reduced. Where dehumidification of the air is required, it is necessary to cool the air below its dewpoint, with the result that reheating of the air may be required before the air is passed into the space. One method that has been used to reheat the conditioned air is to recirculate some of the air in the space and mix this air with the air that has been cooled. Another system has been to by-pass some of the fresh air around the cooling coils and mix it with the cooled air, thereby reheating this air. In systems of this type, it is customary to control the temperature of the cooling coils in accordance with the amount of dehumidification that is required, and to control the proportion of air that is passed over the cooling coils, and the proportion of recirculated or by-passed air, in accordance with the temperature in the space being conditioned. In a system of this type, as the proportion of fresh air and of return or by-passed air is varied, the load on the cooling unit varies, thus requiring a varying tonnage of the refrigerating unit to cool the cooling unit. The variation in the refrigeration tonnage may be so marked in such a system that when maximum tonnage is required to effect the desired amount of dehumidification, that due to the temperature within the space, there may be a very small amount of air passing over the cooling unit, so that a very small temperature rise in the cooling unit results, and the tonnage of the refrigeration system may be reduced far below the maximum value obtainable when the maximum amount of fresh or outdoor air is going through the cooling unit.

I have overcome this defect which is common to such systems by providing a fixed by-pass around the cooling unit so that the same amount of air is at all times passed over the cooling unit and by-passed around the cooling unit. The cooling unit is controlled by the outdoor wet bulb temperature, and variations in the requirements for sensible heating are taken care of in the first place by providing a refrigerant air heater and liquid cooler, which may comprise a coil in the air conditioning chamber downstream from the cooling unit through which refrigerant passes before it reaches the expansion valve of the

refrigeration system, whereby the air is reheated and the liquid in the cooling coil is further cooled to give a lower dewpoint without affecting the delivery air temperature. In this way, the delivery air temperature may be effectively controlled without affecting the tonnage on the refrigeration system. As the outdoor wet bulb temperature varies, the demands on the cooling unit vary, and the tonnage may be controlled by controlling the expansion valve and/or by employing a slicing control for the cooling unit as taught in my Patent 1,673,552, issued June 12, 1928.

I have also devised various means for economically providing for further reheating of the conditioned air if necessary. The various means may be operated in sequence, the air heater liquid cooler above mentioned being the first one. The cooling water which has been used for pre-cooling the air entering the air conditioning chamber may next be used for reheat purposes, this water having been warmed by removing heat from the air entering the chamber. This same water may also be used for cooling the condenser of the refrigeration system. If more reheating is required, some of the air may be caused to circulate through a jacket surrounding the motor which drives the compressor of the refrigeration system. In this way, the motor is cooled making for more efficient operation thereof, and this heat, which would otherwise be wasted, is utilized for reheat purposes. Under severely abnormal conditions, it may be required to provide for further reheating of the air, and a steam coil may be used to provide this additional reheating. Under normal conditions, however, the other reheating means will be sufficient to reheat the air, so that the expense of reheating is reduced to a minimum.

It is accordingly an object of my invention to provide an air conditioning system wherein an air conditioning chamber having a cooling unit therein is provided with a fixed by-pass around the cooling unit, the cooling unit being controlled in accordance with outdoor wet bulb temperature, the indoor dry bulb temperature being controlled by suitable reheating means, whereby proper conditions of temperature and humidity are maintained within the space being conditioned, and whereby the load on the refrigeration system is unaffected by the requirements for sensible cooling in the space for a given outdoor wet bulb temperature, thus keeping the tonnage of the refrigeration system at a minimum. The cooling unit may also be controlled from the outdoor dewpoint temperature.

Another object of the invention is the provision of an air conditioning system wherein new and economical means for reheating the cooled and dehumidified air are provided.

Another object of the invention is the provision of an improved control arrangement for an air conditioning system.

Other objects will become apparent upon an examination of the specification, claims and appended drawing, wherein is illustrated a preferred form of the invention.

Referring more particularly to the drawing, an air conditioning chamber is represented generally by the reference character 10. A fan 11 driven by a motor 12 is provided for drawing fresh air through the inlet 14 of the air conditioning chamber 10 and discharging it from the outlet 13 into a space 15 to be conditioned. Located at the inlet 14 of the chamber 10 is a counter flow heat transfer coil 16 for precooling the air entering the chamber. This coil is connected by means of a pipe 17 to a counter flow heat transfer coil 18 which serves to reheat the air which passes over the cooling elements to be described.

The means for cooling and dehumidifying the air passing through the chamber 10 may comprise a coil 20 which forms the evaporator of a refrigeration system. This system may include a compressor 21 driven by a motor 22, compressor 21 being connected to a condenser 23 by means of a pipe 24, the outlet of this condenser being connected by means of valve 25 and pipe 26 to the expansion valve 27 from which expanded refrigerant flows to the evaporator 20. The evaporated refrigerant flows through a pipe 28 from the outlet of the evaporator to the inlet of the compressor 21. The compressor motor 22 may be controlled in any well known manner, and for purposes of illustration I have shown a suction pressure controller 30 which may comprise a bellows 31 connected by a tube 32 to the inlet of the compressor, this bellows operating a mercury switch 33 mounted on a lever 34 biased against the bellows by means of a spring 35. As the suction pressure of the compressor drops to a predetermined low value, the bellows 31 contracts and tilts the mercury switch to the circuit breaking position, thus stopping the operation of motor 22. This form of control is well known and it will be understood that any other conventional controlling means for the motor 22 may be used. The condenser 23 is cooled by water which flows through the precooling coil 16 and pipe 17. This water may flow either through the reheat coil 18 or through a by-pass 38 around the coil 18 and through the pipe 39 to the condenser 23, the water leaving the condenser through a pipe 40.

The cooling effect of the evaporator 20 is controlled by the expansion valve 27 in a manner to be described and also by means of the spray 42 mounted in front or up stream of the evaporator 20. Water is sprayed from the spray 42 onto the evaporator 20, the spray being controlled by means of a valve 43 controlled in a manner to be described. The amount of water sprayed onto the evaporator 20 will control the cooling and dehumidifying effect of the evaporator as more fully set out in my Patent 1,673,552, issued January 12, 1928. The cooling effect of the evaporator will decrease as the formation of frost on the evaporator increases. By spraying water onto the evaporator, the formation of frost on the evaporator may be reduced with the result that the cooling effect thereof is increased as the

supply of water sprayed thereon increases in the manner fully set forth.

5 A by-pass 45 is provided for by-passing a fixed amount of the air entering the chamber 10 around the evaporator 20. This by-pass may be of any suitable size depending upon the requirements of the system and may, for example, be of sufficient size that it will by-pass 50 per cent of the air entering the chamber 10 although for 10 some systems it may be desirable to by-pass more or less air. It will, however, be of a size which will most effectively work for a given system in a given locality.

15 Mounted in the path of air leaving the evaporator 20 and flowing through the by-pass 45 is a set of eliminator plates 46 for removing particles of water from the air. A suitable sump may be provided below the eliminator plates, this sump being provided with a drain 48. These eliminator 20 plates may be of any suitable form such as the form illustrated in the drawing, or they may be shaped as illustrated in my aforementioned patent. Mounted just down stream of these eliminator plates is a coil 50 for reheating the air 25 leaving the evaporator 20. The inlet of this coil is connected by means of the valve 25 with the outlet of the condenser, and when the valve 25 is properly set the refrigerant leaving the condenser will first flow through the coil 50 before it reaches the expansion valve 27. Valve 25 is a 30 three-way valve and in one extreme position all of the refrigerant will flow through the coil 50, in the other extreme position none of the refrigerant will flow through this coil, and between these extreme positions the amount of refrigerant flowing through the coil will be proportional to the setting of the valve. It will be understood that when the refrigerant is caused to flow through the coil 50, the refrigerant will be further cooled below the temperature at the condenser, in this manner reheating the air passing thereover and causing the refrigerant entering the evaporator 20 to be further cooled, thus increasing the cooling and dehumidifying effect of 45 the evaporator.

50 The coil 18 is mounted just downstream of the coil 50 and forms a second reheat means for the cold and dehumidified air. The flow of water through this coil is controlled by a three-way valve 52 similar to the valve 25. In one position of this valve, all the water flowing to the condenser 23 flows through the pipe 38 which is mounted outside of the chamber 10, and in the other extreme position the water all flows through the coil 18. Since this water has been used for precooling the air by means of the coil 16, it will be understood that this water is relatively warm when it reaches the coil 18 and will have a heating effect on the air passing thereover and this water will also be cooled so as to increase the efficiency of the condenser 23 when the water flows through the coil 18.

55 The heat generated by the driving motor 22 for the compressor 21 may also be utilized for reheating the air. A casing may be provided about the motor through which air is caused to circulate by means of conduits 52 and 53. The flow of air through these conduits may be controlled by dampers 54 operated in a manner to be described. When the dampers are in wide open position, there will be little or no tendency for the air to flow through the conduit 52 to the casing surrounding the motor but when the dampers are moved towards closed position some of the air will tend to flow through the conduit

52 to the motor casing and thence through the conduit 53 back to the chamber 10. In this manner, the heat generated by the motor is effectively utilized and at the same time the motor is cooled.

Under normal conditions the reheating devices described will be sufficient to maintain the temperature of the air leaving the chamber 10 sufficiently high for proper comfort conditions in the space 15. Under extreme conditions, however, it may be necessary to provide for further reheating of the air and for this purpose a steam coil 55 may be provided, the flow of steam through this coil being controlled by a valve 56.

Mounted directly up stream of the eliminator plates 46 is a dewpoint controller which may be composed of a bulb 58 connected by means of a capillary tube 59 to a bellows 60, this tube, bulb, and bellows being filled with a suitable volatile fluid whereby variations in the temperature in the bulb 58 will cause the bellows 60 to expand or contract. Since the bulb 58 is located just in front of the eliminator plates, it will be subjected to a spray caused by the separation of the water particles from the air and this bulb will, accordingly, respond to the dewpoint temperature of the air flowing thereover. A bell-crank lever pivoted at 61 has an arm 62 biased against a pin or projection 63 connected to the top of the bellows by means of a spring 64. The other arm 65 of the lever is arranged to sweep over a resistance element 66, the portion of the arm which engages the resistance being suitably insulated from the rest of the lever. As the dewpoint temperature in the bulb 58 decreases, the bellows 60 will contract and the arm 65 will move to the left under the influence of the spring 64, and conversely as the dewpoint temperature increases arm 65 will be caused to move to the right. This controller is arranged to control the operation of a step controller generally indicated by the reference character 70. This controller may include a proportioning motor 71 which may be of the type illustrated in Patent No. 2,028,110 issued to D. G. Taylor on January 14, 1936. Briefly, this motor may comprise a pair of armatures operated by selectively energized field windings, the direction of the rotation of the motor depending upon which of the field windings is energized. A pair of opposed balanced relay coils is connected together at one end, the junction of these coils being connected to the motor terminal 72 and the opposite ends of the coils being connected to the motor terminals 73 and 74. These relay coils control the energization of the two field windings and when one coil is energized to a greater extent than the other, the motor is caused to rotate in one direction or the other depending upon which of the coils is the more highly energized. When the coils are equally energized, neither field winding is energized and the motor remains at rest. Leads 75 and 76 are connected to a suitable source of power, not shown, and serve for energizing the field windings as well as the relay coils, the ends of the relay coils being connected to the source of power. The resistance 66 is connected in parallel with these relay coils, the left end of the resistance being connected to the terminal 73 by means of conductors 77 and 78, and the right end of the resistance being connected to terminal 74 by means of conductors 79 and 80. The junction of the relay coils is connected by means of conductors 81 and 82 to a center tap resistance 83 over which the arm 65 passes.

It will now be apparent that when the arm 65 is in the mid position illustrated, the relay coils connected to the motor terminals will be equally energized and the motor will remain at rest. If the arm 65 is caused to move to the right or left by reason of a change in the dewpoint temperature of the air passing over the bulb 58, the relay coils will become unbalanced and the motor will be caused to rotate. The motor 71 also includes a balancing potentiometer which is connected in parallel with the relay coils, the arm of which is caused to move by the motor 71 in a direction to counteract the effect of the potentiometer 66 so that after the motor has operated a sufficient length of time, the balancing potentiometer will counteract the effect of potentiometer 66 and the relay coils controlling the operation of the motor will again be equally energized. In this manner, the motor 71 is caused to operate an amount proportional to the movement of arm 65 over the resistance 66 and in a direction depending upon this movement.

A second potentiometer 85 is connected in parallel with the potentiometer 66. The control arm 86 of this potentiometer is pivoted at 87 and has a portion 88 biased by a spring 89 against a pin 90 projecting upwardly from the bellows 91. This bellows is connected by means of a capillary tube 92 to a bulb 93 which is mounted outdoors, the tube, bulb, and bellows being filled with a suitable volatile fluid. The bulb 93 responds to the wet bulb outdoor temperature and may be provided with a suitable cloth 94 wrapped around the outside thereof, this cloth being kept moist by means of a tank 95 or any other suitable and well known means may be employed for causing the bulb 93 to respond to the wet bulb outdoor temperature. An increase in outdoor wet bulb temperature causes expansion of bellows 91 and movement of arm 86 to the right over resistance 85. Upon a decrease in outdoor wet bulb temperature, arm 86 moves to the left over resistance 85. If desired, bulb 93 may be replaced by the bulb of a dewpoint temperature controller or other device for indicating dewpoint, such as described in Labus and Crawford Patent No. 2,106,101 issued January 18, 1938. The arm 86 is connected by means of the conductor 98, variable resistance 99 to the junction of conductors 81 and 82. The right end of the resistance 85 is connected by conductor 101 to the junction of conductors 77 and 78 and the left end of the resistance 85 is connected by means of conductor 102 to the junction of conductors 79 and 80. Since the potentiometers 85 and 66 are connected in parallel to the motor 71, it will be apparent that each will exercise a controlling function on the motor. By reason of the resistance 99 connected in series with the arm 86 of the wet bulb responsive potentiometer, this potentiometer will have less effect for a given movement thereof than will the potentiometer 66. In other words, a small movement of the arm 65 will cause the motor 71 to operate from one extreme position to the other whereas it will take a relatively great movement of the arm 86 to cause the same movement of the motor. Potentiometer 85 is therefore a compensating potentiometer and has the effect of shifting the control range of the potentiometer 66 in accordance with variations in outdoor wet bulb temperature. In other words, as the wet bulb temperature rises causing movement of arm 86 to the right, the control range of the potentiometer 66 will be shifted to the right so that a higher dewpoint temperature will

be maintained at the bulb 58. The resistance 83 insures that the operating differential of the arm 65 will be substantially the same regardless of whether the control point is at the center of the resistance 66 or at either end thereof.

Operated by the motor 71 are switch arms 105 and 106 cooperating with resistance elements 107 and 108, respectively. These resistance elements are so arranged as to be sequentially engaged by the arms. In other words, the resistance element 108 is not engaged by the arm 106 until the arm 105 has moved from the extreme left end of the resistance 107 to the extreme right end, as illustrated. Arm 105 and resistance element 107 from a control potentiometer for a proportioning motor 110 similar to the motor 71. An arm 111 is operated by the motor 110 and is connected by means of a link 112 with the stem 113 of valve 27. The position of arm 111 and consequently of the valve 27 will depend upon the relative position of the arm 105 with respect to the resistance 107. When the arm 105 is in the extreme right end of resistance 107, as illustrated, the valve 27 will be in wide open position and as the arm 105 is caused to move to the left the valve 27 will close an amount proportional to this movement.

The arm 106 and resistance 108 control a proportioning motor 115 which is connected by means of arm 116 and link 117 to stem 118 of valve 43. When the arm 116 is in the position illustrated, the valve 43 is in its closed position but as the arm 106 begins to move over the resistance 108 the arm 116 is rotated counter-clockwise an amount proportional to this movement and the valve 43 is opened an amount proportional to the extent of the movement of arm 106.

The operation of the evaporator 20 and spray 42 may now be briefly summarized as follows: assuming that the outdoor wet bulb temperature is at 70°, the dewpoint controller 58 will operate to maintain a dewpoint temperature of approximately 54°. Should the dewpoint temperature rise above this value, arm 65 will move toward the right and cause operation of motor 71 in a direction to move the arms 105 and 106 in a clockwise direction. Valve 27 is already wide open and further movement of arm 105 in a clockwise direction will have no effect on the motor 110. As the arm 106 moves in a clockwise direction, the motor 115 operates to open the valve 43 an amount proportional to the extent of this movement whereupon water is sprayed onto the evaporator 20 at a rate depending upon the movement of the arm 106, thus increasing the dehumidification effected by the evaporator 20 in the manner set forth in my aforementioned patent. Should the dewpoint temperature at 58 decrease below the desired temperature, motor 110 will operate to move arms 105 and 106 in a counter-clockwise direction. The water issuing from spray 42 will gradually decrease and if the dewpoint temperature has not risen to the desired value when this water is completely shut off, the controller 105 will start to operate the motor 110 to shut down on the expansion valve 27, thus decreasing the amount of refrigerant supplied to and the dehumidifying effect of the evaporator 20 still further until the dewpoint temperature at 58 has reached the desired value. As the outdoor wet bulb temperature rises, the control point of the potentiometer 66 will rise to maintain a higher dewpoint at 58, and conversely, if the outdoor wet bulb temperature falls the con-

trol point of the potentiometer 66 is lowered. The amount of dehumidification and cooling required by the evaporator 20 will depend primarily upon the outdoor wet bulb temperature as will be apparent since this temperature is a measure of the total heat within the air and it will therefore be seen that for a given outdoor wet bulb temperature the load on the refrigeration system will remain substantially constant since the amount of air passing over the evaporator is the same at all times.

Mounted within the space being cooled is a thermostat indicated generally by the reference character 120. This thermostat may comprise 15 a bimetallic element 121 having an arm 122 connected thereto and operated thereby in accordance with variations in the dry bulb temperature of the air within the space 15. Operated by the thermostat 120 is a proportioning motor 125 of 20 a step controller generally designated by the reference character 126. The terminal 128 of this motor is connected by means of conductors 130 and 131 to the center tap resistance 132 over which the arm 122 of the thermostat slides. 25 Motor terminal 127 is connected by means of conductors 133 and 134 to the right end of a resistance element 135 which forms the control potentiometer resistance for the motor 125. The opposite end of this resistance is connected by 30 means of conductors 136 and 137 to the terminal 129 of the motor. If the temperature within the space 15 varies, the motor 125 operates in the same manner as the motor 71 as will be apparent. The effect of the thermostat 120 on the motor 127 may be compensated by the outdoor dry bulb 35 temperature responsive controller 140. This controller may comprise a bellows 141 connected by means of capillary tube 142 to the bulb 143, this tube, bulb, and bellows being provided with a suitable volatile fill. The control arm 145 is 40 biased by means of spring 146 into engagement with the pin 147 carried by the bellows and this arm is caused to move over the resistance 150 in response to changes in the outdoor dry bulb 45 temperature. The arm 145 of this controller is connected by means of conductor 151, variable resistance 152 and conductor 153 to the junction of conductors 131 and 130. The right end of this resistance is connected by means of conductor 154 to the junction of conductors 133 and 134, and the opposite end of this resistance is connected by means of conductor 155 to the junction of conductors 136 and 137. It will, accordingly, 50 be seen that the resistance 150 and arm 145 form a potentiometer connected in parallel with the potentiometer 135 to the motor 125 and this controller serves to shift the control range of the controller 120 in accordance with variations in outdoor dry bulb temperature. Thus as the outdoor dry bulb temperature falls, the control range of the thermostat 120 will be lowered or shifted towards the right. It will therefore be seen that the motor 125 will operate in accordance with the outdoor dry bulb temperature to maintain the indoor dry bulb temperature at a value which depends upon the outdoor dry bulb 55 temperature.

Operated by the motor 125 are the arms 160, 161, 162, and 163 which are arranged to move sequentially over the resistance elements 164, 165, 166, and 167, respectively. The arm 160 controls the operation of a motor 170 which may be a proportioning motor. An arm 171 operated by the motor 170 is connected by a link 172 to the stem 173 of the three-way valve 75

25. When the arm 160 is in the position illustrated, the arm 171 is in one extreme position and the three-way valve is likewise in an extreme position in which no refrigerant is permitted to flow through the reheat coil 50. Should the indoor dry bulb temperature start to fall below the desired value, the arm 160 is moved in a clockwise direction by the motor 125 which in turn causes the motor 170 to operate to move the valve 25 in a direction to permit the flow of refrigerant through the coil 50, the amount of refrigerant flowing through the coil depending upon the extent of movement of the arm 160.

The arm 161 controls the operation of the proportioning motor 175, the arm 176 which is operated thereby being connected by a link 177 to the valve stem 178 of the three-way valve 52. In the position illustrated, the three-way valve is in one extreme position in which no water is permitted to flow through the coil 18 but all the water flows through the by-pass 38. Should the temperature in the space 15 drop sufficiently so that arm 161 begins to move over resistance 165, this valve is operated to permit water to flow through the coil 18 at a rate proportional to the amount of movement of arm 161 over the resistance 165.

The arm 162 controls a proportioning motor 180 having an arm 181 operated thereby and connected by means of a link 182 to the dampers 54. When the arm 162 is in the position illustrated, the dampers are positioned to permit maximum flow of air therethrough. These dampers will begin to move towards closed position as the arm 162 begins to move over the resistance 166 thus causing some of the air to flow through conduit 52, motor casing 22, and conduit 53. The arm 163 controls the operation of the proportioning motor 185, the arm 186 of which is connected by means of the link 187 to the stem 188 of the valve 56 which controls the supply of steam or other heating medium to the coil 55. This valve will remain in closed position until such time as the arm 163 begins to move over the resistance 167 whereupon it will begin to open and permit the flow of steam or other heating fluid through the coil 55, the amount of steam which flows through this coil being dependent upon the position of the arm 163 with respect to this resistance 167.

It will be noted that the resistances 164 and 167 are so arranged that each successive resistance will not be engaged by its control arm until the control arm of the preceding resistance has moved through the full range of the resistance. In other words, resistance 165 will not be engaged by the arm 161 until arm 160 has moved to the extreme right end of resistance 164 and so on. It will therefore be seen that the various reheating devices will be operated sequentially. Thus if the space temperature drops below the desired value, the coil 50 will be utilized for reheating purposes and if after the valve 25 is positioned to permit all of the refrigerant flowing to the evaporator 20 to flow through the coil 50 the space temperature has not risen to the desired value, then the water flowing through pipe 17 will begin to flow through the coil 18 and additionally reheat the air passing thereto. If the temperature in the space is still too low after all the water flowing through the pipe 17 has passed through the coil 18, the dampers 50 will begin to move towards closed position and cause some of the air passing through the

chamber to pass through the conduit 52 to the casing of motor 22 and back through conduit 53 to the chamber 10. If the space temperature is still too low after the dampers are moved to their extreme position causing a maximum flow of air through the casing of motor 22, then steam or other heating medium will be admitted to the heating coil 55 in an amount sufficient to raise the space temperature to the desired value. Under ordinary conditions, however, the space temperature will rise sufficiently before the valve 56 starts to open so that the desired degree of reheating will be accomplished without the necessity of utilizing any extra heat supply, thus increasing the efficiency of the system appreciably. The use of the various reheating devices with the exception of the coil 55 all tend to increase the efficiency of the system. The flow of refrigerant through the coil 50 will tend to lower the temperature of the coil 20 thus increasing its capacity and the flow of water through the coil 18 will increase the cooling effected by the condenser 23 which will increase the efficiency of the refrigeration system. Also by causing a circulation of air through the casing of motor 22, this motor will be cooled and the heat generated therefrom will serve a useful purpose which also increases the efficiency of the system.

With the various control devices in the positions illustrated, the outdoor wet bulb temperature is approximately 70° and the outdoor dry bulb temperature is approximately 100°, the indoor dry bulb temperature is approximately 85° and the dewpoint at 58 is about 53½°. The amount of refrigerant flowing through the evaporator 20 is at a maximum, the spray 42 is shut off and none of the reheating devices are in operation, the by-pass 45 providing the necessary amount of reheat to maintain the space temperature at the desired value which may be assumed to be 85° for an outdoor dry bulb temperature of 100°. As the outdoor dry bulb temperature drops, the control range of thermostat 120 will shift to the right and when the outdoor dry bulb temperature drops to 70°, the indoor dry bulb temperature will be lowered from 85° to 72°. Likewise, as the outdoor wet bulb temperature drops to 60°, the control point of the dewpoint controller 58 will drop to 50° and as the outdoor wet bulb temperature rises to 80°, the control point of the dewpoint controller will rise to 57°.

Since there is always a uniform amount of air flowing past the evaporator 20 and since the dehumidifying effects of the evaporator is controlled in accordance with the outdoor wet bulb temperature, the available tonnage of the refrigeration system available for dehumidification may be kept at a maximum for maximum requirements. Should the sensible load within the space 15 decrease due to a decrease in the sun effect or a decrease in the number of persons within the space without any change in the outdoor dry bulb temperature the temperature of the air entering the chamber 15 will have to be increased in order to compensate for the decreased sensible cooling load. The valve 25 will be operated to increase the amount of refrigerant flowing through the coil 50 which will tend to raise the temperature of the air passing thereby and at the same time it will lower the cooling effect of the evaporator 20, which will tend to slightly lower the dewpoint temperature at 58. Since the air leaving the chamber 10 has a some-

what higher temperature but a somewhat lower dewpoint, the relative humidity of the air will be maintained at a comfortable value and it is therefore seen that the relative humidity of the space is effectively controlled without the provision of any humidity responsive devices.

The provision of the variable resistances 99 and 152 in the circuits to the control arms 86 and 145 make possible the adjustment of the effect of these controllers with respect to the controllers 65 and 120. Other variable resistances may be also provided in the circuits to the controllers 66 and 120 to shift the control range of these controllers for a given position of control arms 86 and 145, if desired.

It should be understood that the temperature values maintained by the various controllers are illustrative only and any desired temperature schedule may be set up in actual practice.

While I have illustrated a preferred form of my invention, many modifications may become apparent to those skilled in the art and I wish it to be understood that my invention is limited only by the scope of the appended claims.

I claim as my invention:

1. In an air conditioning system, an air conditioning chamber, means including an evaporator of a refrigeration system for cooling and dehumidifying air passing through said chamber, said refrigeration system also including a condenser, a precooling coil in the path of fresh air entering said chamber, means utilizing the fluid leaving said coil for cooling said condenser, means responsive to the conditions in the space being cooled, and means under the control of said last named means for utilizing the fluid leaving the precooling coil for reheating the air leaving the cooling means before the fluid reaches the condenser.

2. In an air conditioning system, the combination of, an air conditioning chamber, cooling and dehumidifying means for cooling and dehumidifying air passing through said chamber including a refrigerating apparatus having evaporator means for cooling and dehumidifying the air, a condenser for condensing refrigerant, a com-

pressor for circulating refrigerant through the evaporator means and condenser and an electric motor for operating the compressor, a precooling coil in the path of fresh air entering said chamber, 5 means utilizing the fluid leaving said coil for cooling said condenser, reheating means including means utilizing heat generated by the electric motor and the fluid leaving the precooling coil before the fluid reaches the condenser for reheating the cooled and dehumidified air, a controller responsive to the temperature of the cooled and dehumidified air for regulating the cooling and dehumidifying action of the cooling and dehumidifying means, and a controller responsive 10 to the dry bulb temperature of the air in the space being cooled for controlling the reheating means to regulate the dry bulb temperature of the space, both of said controllers coacting to maintain desired dry bulb temperature and relative humidity conditions and hence effective temperature conditions in the space.

3. In an air conditioning system, the combination of, an air conditioning chamber, cooling and dehumidifying means for cooling and dehumidifying air passing through said chamber including refrigerating apparatus having an evaporator and a condenser, a precooling coil in the path of fresh air entering said chamber, means utilizing the fluid leaving said coil for cooling said condenser, reheating means including means utilizing the fluid leaving the precooling coil before the fluid reaches the condenser for reheating the cooled and dehumidified air, a controller responsive to the temperature of the cooled and dehumidified air for regulating the cooling and dehumidifying action of the cooling and dehumidifying means, and a controller responsive to the dry bulb temperature of the air in the space being cooled for controlling the reheating means to regulate the dry bulb temperature of the space, both of said controllers coacting to maintain desired dry bulb temperature and relative humidity conditions and hence effective temperature conditions in the space.

ROBERT B. P. CRAWFORD.
